SIGNALING APPARATUS

David Perlman, Jersey City, N. J.

Application November 15, 1930, Serial No. 495,922

18 Claims. (Cl. 175—356)

My invention relates to novel apparatus for and methods of signaling and new and improved apparatus therefor.

Specifically, my invention relates to a new and improved transformer for high and low voltage secondary output and multi-functional operation and a combined high and low speed current interrupter and pole changer as well as novel methods of operation thereof for providing a greater degree of dependability of the transformer operation, even during abnormal conditions, such as short-circuiting or burning out of the primary, or failure of the main power supply.

In the application of railway and other signaling, it is of utmost importance that the signaling apparatus operate with substantial safety, as a single failure of the signaling apparatus may prove more damaging in property and in loss of life than is commensurate with the cost of the signaling system.

To this end, attempts have been heretofore to develop signaling apparatus which will perform with a high degree of accuracy under all operating conditions. These, however, have resulted in complications, which have destroyed the very purpose of the idea.

Accordingly, it is an object of my invention to provide novel apparatus for and methods of signaling, which will give high degree of operating safety.

A further object of my invention is to provide novel transformer apparatus and methods of operation thereof and to operate relay switches, high and low speed interrupters, pole changers, mercury switches, etc., in addition to transformer functions.

Still a further object of my invention is to provide new and improved signaling means for operation in railway and other related signaling systems.

Still a further object of my invention is to provide new and improved signaling circuits which will insure 100% accuracy of operation under all conditions and will provide ample warning in the event that any part of, or the entire system, fails.

Further objects in my invention are such that will appear in a more detailed description of the invention, which is to follow in the specification, in which:

Figure 1 shows a circuit diagram embodying a schematic detailed view, partly in section of an improved transformer employed according to the invention.

Figure 2 is a side view of the transformer shown in Figure 1.

Figure 3 is a modified construction of my transformer in schematic detailed view, partly in section built with three cores and provisions to operate several independent electro-mechanical devices.

Figure 4 is a top view of Figure 3 showing the relay switch and magnetic interrupter.

Figure 5 is a partial front view of a transformer according to Figure 3 showing hinged armature and mercury switch combination with adjustable time controlling paddle.

Figure 6 is a side view of a polarity changing drive mechanism with mercury tube switch to be mounted on top of transformer of Figure 3.

Referring to Figure 1, a relay 1 is shown connected over a signaling line to a control mechanism operated in accordance with the signaling conditions to be controlled, in a manner well known in the art. This may be some arrangement whereby a train, entering a section, de-energizes in a well-known manner the normally energized relay 1, or if used in connection with dispatcher control, may be a circuit arrangement, whereby a dispatcher, by key operation, de-energizes the normally energized relay 1. The relay 1, upon de-energizing in accordance with any operation, as indicated in the illustration, causes its armatures 19 and 21 to drop back to their back contacts 15 and 17, respectively. As a result of the armatures 19 and 21 engaging their back contacts, 15 and 17 respectively, an energizing circuit is completed from a source of alternating current shown at 14 over the back contact 15 and armature 19 through a thermostatic circuit interrupter or flasher 4 through the primary winding 3 of the transformer and back to source 14.

The interrupter 4 is arranged to periodically open and close this circuit for the desired flashing effect immediately after the circuit is closed, as described above and an alternating current accordingly flows intermittently through the primary winding 3 so long as the relay 1 remains de-energized.

The alternating current through the winding 3 induces a current in the secondary winding 9, as a result of which a voltage is impressed across the neon tubes 13. It will be noted that there are two neon tubes connected in parallel across this circuit. As is well known, the characteristics of neon gas tubes are such that no two tubes have exactly the same resistance and, accordingly, when a discharge starts in one of the tubes, that tube will continue in operation and the other tube will remain non-operative thus in-

creasing the safety of response of the signaling device.

A further result of the energizing of the primary winding 3 by the alternating current is to operate the relay switch armature 83, but this has no effect at this time, as will appear in full hereinafter. When, however, for any reason, an abnormal condition occurs in the system, such as a breakdown in the transformer winding, failure of the power system, etc., the armature 83 by its operation functions to correct for this breakdown condition, in switching on the emergency current supply on the emergency circuit.

In order to illustrate the case further, it will be assumed that there has been a failure in the primary winding 3.

It will be noted that, in addition to the engagement of contact 15 by armature 19, upon the de-energization of relay 1, a further result of the operation of the relay 1 is to cause armature 21 to engage contact 17. A circuit is thereupon completed from emergency battery 2 through thermostatic circuit flasher 6 to the contact 17 and armature 21 through the primary winding 25 5—5 of the emergency transformer circuit, back contact and interrupter armature 88, relay armature 83 and its back contact, and back to battery 2.

Under normal conditions, with the core 11 energized by the alternating current and the armature 83 held away from its back contact, this circuit is not completed, by reason of the fact that the armature 83 disengages its contact. The magnetic conditions of the winding 3 are such that during current operations thereof, it holds the armature 83 disengaged from its back contact.

Accordingly, winding 5 is normally non-operative while the normal operating conditions obtain. When, however, as assumed above, a failure in the winding 3 occurs and the armature 83 closes to its back contact, an energizing circuit is completed through the winding 5.

One of the effects of the current flowing through the winding 5 is to operate the interrupter 88 in this circuit, thereupon producing pulsating currents in the winding 5. These pulsating currents induce an E. M. F. in the secondary 9, which is, accordingly, impressed across the neon tubes 13 as in the first case.

The secondary of the transformer is arranged in loose coupling relation, so that under constant short circuit it will not become injured. Moreover, the two cores are placed in such a mechanical relation, that should the primary winding 3 be burnt out, or short circuited, the secondary winding 9 will operate from the emergency winding 5 without any decrease of safety or undue consumption of primary current.

From the above it is seen that the transformer of the present invention is quite different from the usual type, inasmuch as it performs other functions besides the usual function of transforming the voltage. Furthermore, the main transformer action can be secured alternately from an alternating current supply or from an interrupted direct current supply, these supplies being entirely independent of each other. A more detailed description of the transformer principles will follow.

Figures 1 and 2 also show the two arm transformer construction comprising two groups of punchings, group 11 of which is of U-shape and group 12 of straight shape and separated from the first group by air gaps 13 and 14. The

group of punchings 11 carries the primary winding 3, while the group of punchings 12 carries the emergency primary winding 5 and the secondary winding 9. By providing, in addition, the air gaps 13 and 14 for separating the magnetic core of the primary and the secondary, an arrangement is obtained whereby, even if the primary winding 3 is short circuited or burned out, the satisfactory energization of the secondary 9 from the emergency primary 10 winding 5 will not be prevented. The punchings may be held together by angle frames 16 and 17, the latter also serving as supports for the various relay and buzzer contacts and other devices. In this manner, by providing air-gaps 13 and 14 at a suitable distance between the core 11 and the core 12, sufficient loose coupling of the secondary winding may be secured, preventing reaction from the primary upon the secondary during short circuit of the primary winding and insuring proper function of the emergency winding and secondary winding under all circumstances. In order to prevent excessive leakage of the magnetic flux produced by the main primary winding and force a substantial amount of the primary flux through the secondary winding despite the provision of a rather loose coupling, I have found it preferable to enlarge the cross-section of the central portion 15 for the core 11 in excess of the cross-section of the remaining portions 24 of the magnetic circuit. In this manner a maximum of transformer efficiency is obtained with sufficiently large air-gaps to provide the necessary loose coupling for preventing objectionable reaction on the windings carried by the core 12 in case of a short circuit or other disturbance, such as an excess or surge voltage, occurring in the main primary winding.

A plurality of metal bridges 18, 19 and 80 are mounted on the frames 17 on one side of the transformer, as shown more clearly in Figure 2. These bridges are insulated from the frames 17 by means of insulating washers 81. The bridge 19 supports the emergency relay spring 82, which carries the armature 83, having a contact 84 cooperating with a contact 85, supported on the bridge 18. The bridge 19 also supports, by means of an independent screw 86, the buzzer spring 87, which carries the armature 88, having a contact 89 cooperating with a contact 90 supported on the bridge 80. Other relays or controls may be mounted on the frame 16 on the opposite side of the transformer, in the event that further action is desired.

Referring to Figures 3, 4 and 5, I have shown a device using mercury switches operated from the common transformer core and serving as flasher switches in place of the thermostatic devices shown in Figure 1. The construction consists of armatures, the time period operations of which, that is, the time taken to move from energized to de-energized position and vice versa, may be varied. Specifically, adjustable paddles 108, 109 extend downward from the hinged armatures 110 and 111. The paddles are immersed in a jar 112, filled with a suitable liquid such as mercury 113. The jar 112 is provided on its outside frame with a long screw thread 114, to permit the vertical adjustments, whereby the desired time setting motion resistance regulation is obtained. In other words, time periods of operation of the armature from its energized to de-energized position and vice versa are varied. By raising the jar, the time period is increased and by lowering the jar, the time period is decreased. In addi-

tion to this, a further individual regulation is made by the sliding adjustments of the paddle on the armature mounting 115, as seen from Fig. 5 provided with slot 116, in which screws 117 lock the paddles in raised or lowered position. I have furthermore shown in Fig. 5 connecting clips 118a for mounting the mercury tubes and terminal, such as a socket 128, for making the required electrical connections.

10 As will be understood, the armatures carry mercury switches of well known construction, which contain a small quantity of mercury, by means of which a circuit between two electrodes is made and broken as the mercury switch is tilted back and forth.

15 The operating functions of the multi-functioning transformer utilizing the mercury switches are the same as previously described, the only difference being in the additional construction means 20 for mounting and tilting of the mercury switches, to effect the desired making and breaking of the circuits. Armatures 110 and 111 are designed each to carry two or three mercury switches 118, 119, 120, and 121, which may function to control two transformer units such as in Fig. 3 in a structurally combined construction, in which the energizing and secondary windings and the induction coil core are designated by 5a, 9a, and 12a, respectively, alternately, so that, while one transformer circuit is closed, the other transformer circuit is open. Adjustable stops 122 and 123 are provided to regulate the downward motion of armatures 110 and 111.

25 Armatures 110 and 111 function independently 30 of each other, 110 on the main transformer circuit and 111 on the emergency transformer circuit, as follows:

35 Normally, mercury switch 119 is closed and when relay 1 becomes de-energized by the approach of the train, switch 19 will close with contact 15 (see Fig. 1), which permits current to pass the main circuit of winding 3 and magnetically energize the core 71, which will attract hinged armature 110 with mercury switches 118 and 119. 40 The mercury switch is tilted and causes the mercury to flow to the other end and open up the circuit of winding 3, thereby disrupting the magnetic attraction of core 71. Armature 110, returns by tilting back to its normal position by 45 force of gravity of the armature, mercury switches and paddle, thus completing a cycle of operation. Mercury switch 118 is mounted on the same armature, to function in reversed order thus performing an alternate flashing action.

50 A further object of my invention is the provision of means to protect the secondary windings of my transformer from possible rupture or short circuiting and burning-out, due to the higher voltage stress which builds up when operating open circuited, particularly on the emergency winding in case of tube failure.

55 To prevent possible mis-operation, I have provided my transformer at the secondary winding terminals with a suitable safety spark gap 129 (see Fig. 1), permitting the higher tension current to jump across in case of tube failure, thereby assuring the safe operation of the transformer.

60 A further object of my invention is the provision of means to obtain the maximum results 65 from the contact points on the magnetic interrupter operating the emergency circuit of my transformer. It is also my intention to use this improvement on all types of induction coils. In ordinary service, contact points on interrupters 70 become pitted and quite often stick or fuse to-

gether, thereby rendering the device useless and not dependable for important service. This trouble is caused by the unipolar ionization process which carries over the metal from the negative pole contact point to the positive pole contact point, thereby causing the positive contact point to build up ridges with relative pitting unevenness on the negative contact point, which throws the device out of its adjustment, and quite often results in sticking or fusing together of both contacts.

65 To avoid the aforesaid troubles, I incorporated in my multi-functional transformer construction also means for automatic pole changing of current on the contact points, with provision to use 15 especially designed pole changing devices or any conventional design double pole double throw switch with this construction.

70 This very simple and efficient construction can be mounted on the top or bottom of the transformer, and is applicable to any type induction coil for continuous or interrupted operation with a very slight modification.

75 To avoid the possible failures of the conventional designed switches utilizing springs for their motive power, I constructed highly reliable pole changing switches utilizing magnetic attraction and gravitation as their motive power, which is most dependable. The mercury tube switch is very simple and highly reliable in operation. The 80 drum type construction switch is still more reliable with a possible advantage in cost. The construction and operation of my pole changing switches and the motive mechanism is as follows:

85 Referring to Figure 6, when core 72a (see also Fig. 3) becomes energized it causes the hinged armature 130 to swing down. On the armature at 90 131 is pivoted a ratchet pawl 132, causing ratchet gear 133 to turn over one tooth forward in the direction indicated by arrow; a second ratchet pawl 134, pivoted at 135, holds the ratchet gear from slipping back. Pawls 132 and 134 are counterbalanced with weights 136 and 137. Limit stops 138 and 139 prevent pawls from turning over too far. When the core becomes de-energized, the armature returns to its normal position again by gravity means of rod 140, and counterbalancing weight 141 and the armature stop against adjustable abutment 142 thereby completing the cycle of armature operation of the gear 133 rotated through one tooth distance.

100 This armature motion transmits, through the gear train, a very slow revolving movement to the third gear 143 with stud 144 carrying sleeve 145 engaging in fork 146 which is pivoted at 147 and swings up and down on a complete revolution of gear 143. The fork motion actuates by its lever 148 and connecting link 149, any type toggle or tumbler switch including the mercury and other especially designed switches for polarity changing as shown.

105 This mercury tube pole changing switch is actuated by the fork lever 148 and connecting link 149 which is pivoted to tube mounting 162 by pivot 163. Stud 164 pivotally supports the tube mounting 162 with its two sets of spring clips 165 which hold two mercury tube switches 166 and 167, which are connected to change the polarity when tilted from one position to the other.

110 In order to effect a quick tilting-over of the switch, the mounting 162 carries a pointed pin 168 which is engaged in cone 169 over which one end of spring 170 is mounted and is similarly 115

supported on the other end by cone 171 and adjustable pointed screw 172.

The spring, being slightly compressed between the two points, acts to tilt over quickly the switch 5 mounting as its tilting movement, actuated by lever 148, reaches on a nearly straight center line between pointed mounting screw 172, pin 168, and stud 164. The fork slot is made wide enough to accommodate for this forward movement of 10 the switch mounting to effect a greater tilting movement of the switches than is actually caused by the action of gear member 145 upon fork 146.

From the above, it will now be clear that I have disclosed novel transformer cores, of either 15 two or three arms, to suit the particular requirements in which the distribution of the emergency primary winding and secondary windings, the size and proportions of the cores, and the shape and assembly of the cores, are all novel. The 20 cores are constructed with approximate cross section proportions of three or four to one, from primary to secondary cores; and the winding of emergency circuit primaries and secondaries surround the smaller core arms. The winding of 25 the main circuit only covers the large or center core arm, a feature which is a departure from prior transformer construction engineering practice.

With this construction the following important 30 features are obtained: (1) A secondary output of the transformer is obtained by means of an emergency winding and current supply, independently of the main current supply and condition of main winding, which may be short-circuited or burned out; (2) A transformer functioning to the extent of 100% reactance; (3) A transformer in which both sides of the cores are energized.

It will now be evident that I have provided 40 apparatus which is 100% dependable and has very simple means for automatically actuating mercury and other types of switches for any desired purposes, including flashing operations which may be independent or synchronous in 45 operation of more than one unit, including the most dependable and simple kind of time controlling means capable of accurate time setting adjustment.

To avoid the possibilities of failure in complicated mechanical time controlling constructions, 50 I designed my device upon the principles of magnetic attraction and gravitation, plus damping resistance to motion, offered by a suitable liquid such as mercury to a paddle of a suitable size.

Although, for purposes of illustration, I have disclosed the various features of my invention applied to a traffic signaling device, the devices have more general application and I do not propose to limit myself, but only insofar as is set 55 forth in the appended claims.

What I claim is:

1. In a signaling transformer, comprising a main primary winding and an emergency primary winding to become operative upon failure of said main primary winding, a secondary winding, and means whereby said emergency winding can function unaffected and during failure of said main winding.

2. A signaling transformer comprising a main primary winding, an emergency primary winding to become operative upon failure of said main primary winding, a secondary winding and a magnetic core structure carrying said windings arranged to permit independent operation of said

emergency winding unaffected by and during failure of said main winding.

3. In combination, an induction coil, means for periodically energizing said coil, an armature controlled by said coil, a pole changing switch controlled by said armature, a plurality of gravity arms for operating said pole changing switch at a high rate of speed and independently of the rate of operation of said armature.

4. In combination, an induction coil subject 10 to normal operating currents and to occasional abnormal fluctuations, an armature for said coil non-responsive to said normal operating currents and responsive to said abnormal fluctuations, a pole changing switch controlled by said 15 armature and a current controlling contact means carried by said armature.

5. In combination, an induction coil subject to normal operating currents and to occasional abnormal fluctuations, an armature for said coil 20 non-responsive to said normal operating currents and responsive to said abnormal fluctuations, a pole changing switch controlled by said armature and a mercury contact switch carried by said armature.

6. In combination, an induction coil having a pivoted armature arranged to operate between energized and de-energized limit stops, a liquid bath, an arm extending from said armature into said bath, said armature moving to its de-energized position under gravity, said liquid controlling the rate of movement of said armature from one to its alternate position.

7. In combination, an induction coil having a pivoted armature arranged to operate between energized and de-energized limit stops, a mercury bath, an arm extending from said armature into said bath, said armature moving to its de-energized position under gravity, said mercury controlling the rate of movement of said armature from one to its alternate position.

8. In combination, an induction coil having a pivoted armature arranged to operate between energized and de-energized limit stops, a liquid bath, an arm extending from said armature into 45 said bath, said armature moving to its de-energized position under gravity, said liquid controlling the rate of movement of said armature from one to its alternate position and means for increasing and decreasing the depth to which said 50 arm extends in the liquid bath for varying the rate of movement of said armature between stops.

9. In a signaling transformer comprising a first magnet core; a second magnet core; a main primary winding carried by said first core; an emergency primary winding and a common secondary winding carried by said second core, said cores being combined with separating air-gaps therebetween to form a substantially closed magnetic circuit for said main winding and a substantially 60 open magnetic path for said emergency winding; said emergency winding becoming effective upon and during failure of said main winding; and an interrupter means comprising an armature operated by said first core for rendering operative said 65 emergency winding upon failure of said main winding.

10. In a signaling transformer comprising a first magnet core; a second magnet core, said cores being combined with separating air gaps 70 therebetween to form a substantially closed magnetic path comprising said first core and an open magnetic circuit comprising said second core; a main primary winding carried by said first core to be supplied by a source of alternating cur- 75

rent; an emergency primary winding carried by said second core to be supplied by a direct current emergency source; a common secondary winding carried by said second core; an electro-magnetic interrupter for said emergency winding comprising a vibrating armature cooperating with said second core to produce pulsating currents in said emergency winding; and a further interrupter comprising armature means cooperating with said main magnetic circuit for rendering operative said emergency winding upon failure of said main winding.

11. In a signaling transformer as claimed in claim 9 in which said first core is of U-shape spaced from and forming a substantially closed magnetic circuit with said second core.

12. In a signaling transformer as claimed in claim 10 in which said first core is of U-shape and said second core is of bar-shape, both of said 20 cores being combined with separating air gaps therebetween to form a substantially closed magnetic path for said main winding and an open magnetic path for said emergency winding.

13. In a signaling transformer as claimed in claim 10, in which said first core is of T-shape and in which two bar-shaped cores are provided, all of said cores being combined with separating air gaps therebetween to form substantially closed magnetic paths for said T-shaped core and open 30 magnetic paths for said bar-shaped cores; a primary main winding being carried by the central portion of said T-shaped core; a pair of emergency and secondary windings connected in series and carried each by one of said bar-shaped cores.

14. A signaling transformer; a main primary winding to be supplied from an alternating current; an emergency primary winding to be supplied by interrupted direct current upon failure of said main winding; a magnetic core structure 40 carrying said windings; an electro-magnetic interrupter comprising a vibrating armature in the emergency winding circuit operated by said magnetic core; a contact and armature also operated by said magnetic core for normally interrupting said emergency winding during flow of current through said main winding; a common secondary

winding for both said primary winding and said emergency winding; and means whereby said interrupter and said emergency winding operate unaffected by and during failure of said main primary winding.

5

15. In a signaling transformer having a main primary winding; an auxiliary primary winding and a common secondary winding; a magnetic core structure for said windings; means including air-gaps in said magnetic structure whereby 10 said secondary winding is interlinked with said primary winding by a substantially closed magnetic path through said structure including said air-gaps and whereby said emergency winding forms an open core induction coil with said secondary winding; and means in the event that said main primary winding is disabled for automatically rendering said auxiliary winding operative.

16. In a signaling transformer as claimed in claim 10 in which said first core is of U-shape and said second core is of bar shape, both of said cores being combined with separating air-gaps therebetween to form a substantially closed magnetic path for said main winding and an open 25 magnetic path for said emergency winding, the central portion of said U-shaped core having a cross-section substantially in excess of the remainder of the magnetic circuit.

17. A signaling transformer comprising a main 30 primary winding, an emergency primary winding to become operative upon failure of said main primary winding, a secondary winding and a magnetic structure carrying said windings, and means including an air gap in said magnetic structure 35 to permit independent operation of said emergency winding unaffected by the condition and during failure of said main winding.

18. In combination, an induction coil, a vibrator having opening and closing solid contacts for 40 periodically energizing said coil, an armature controlled by abnormal currents through said coil and a pole changing switch for said vibrator controlled by said armature.

DAVID PERLMAN. 45
